[57] **CLAIM**

The ornamental design for a ladder-mounted utility shelf, as shown and described.

DESCRIPTION

FIG. 1 is a perspective view, partly from above, of a ladder-mounted utility shelf embodying my new design.

FIG. 2 is a perspective view of the reverse side thereof.

FIG. 3 is a side view as seen from the right of FIG. 1.

FIG. 1

FIG. 2

FIG. 3
